UNITED STATES PATENT OFFICE.

GEORG SPIESS, OF LEIPZIG-REUDNITZ, GERMANY.

DRIVING CHAIN GEAR FOR RETARDING THE TRANSPORT IN SHEET-FEEDERS.

1,194,562.

Specification of Letters Patent. Patented Aug. 15, 1916.

Application filed June 4, 1915. Serial No. 32,067.

To all whom it may concern:

Be it known that I, GEORG SPIESS, a citizen of the German Empire, and a resident of Leipzig-Reudnitz, Germany, have invented 5 certain new and useful Improvements in Driving Chain Gears for Retarding the Transport in Sheet-Feeders, of which the following is a specification.

This invention has reference to improvements in driving chain-gears for retarding the transport of sheets of paper in sheet feeders.

It is known to be old to impart a retarded motion to the devices for advancing sheets 10 of paper in sheet feeders by means of chain-gears attached to the driving mechanism of the sheet advancing devices. The driving chain-wheel of such chain-gear is eccentrically mounted upon the driving gear so that 15 its pitch circle approximately passes through the axis of the shaft of the driving wheel. By this arrangement the tension of the chain changes continuously.

According to the present invention allowance 20 for these changes is made by mounting one of the chain-wheels around which the chain passes upon an arm which is subject to compulsory displacement.

In order to render the invention entirely 25 clear, reference is had to the accompanying drawing in which:

Figure 1, represents in elevation the arrangement of the devices in one end position. Fig. 2, is a similar view illustrating the devices in another end position. Fig. 3, is a plan view of the device. Fig. 4 shows a modification in one end position. Fig. 5, illustrates this modification in another end position. Fig. 6, is a side elevation of the 40 device shown in Figs. 4, and 5. Fig. 7, is a detail view on an enlarged scale.

Similar characters of reference denote like parts in all the figures.

In the drawing, in Figs. 1, 2 and 3 the 45 driving sprocket-wheel E is eccentrically mounted upon the driving gear H so that its pitch circle approximately passes through the axis of the shaft I of the driving gear H. The chain G passes from the driving 50 sprocket E over the sprocket-wheel F, the guiding roller R and the sprocket-wheels S and T.

According to the present invention the sprocket-wheels S and T are mounted upon 55 a swing arm U in such a manner that the sprocket-wheel S is mounted upon the free

end of the arm U while the sprocket-wheel T is mounted upon the shaft V of the said swing arm. A toothed wheel W is also mounted upon the shaft V which engages a 60 toothed rack X.

The position of the swing arm U is so selected that at the largest maximum distance apart of the shafts of the sprocket-wheels E and F the said swing arm occupies 65 its initial position as shown in Fig. 1. When the chain moves the sprocket-wheel T rotates and accordingly the toothed wheel W which is mounted upon the said shaft V of the sprocket-wheel T. The toothed rack X 70 thereby has a motion in an upward direction and the swing arm U gradually reaches its second end position, as shown in Fig. 2. This is attained by means of the driving gear H¹ for the chain device. The driving 75 gear H¹ is mounted upon the shaft J and an eccentric disk Z is mounted upon the same shaft. A roller Y rests upon the circumferential edge of the eccentric disk Z. This roller Y is mounted upon an arm B formed 80 on the toothed rack X and said arm B has a slot C permitting the arm to move up and down. Assuming that the shaft J rotates then the eccentric disk Z will force the arm B by means of the roller Y into its second 85 or upper end position. The toothed rack X, being integral with the arm B, therefore, will move in an upward direction thereby engaging the gear W upon the shaft V of the swing arm U. Thus the swing arm U 90 is moved from the initial or upper end position into the second or lower end position as shown in Fig. 2; that is from the position shown in Fig. 1 into the position shown in Fig. 2. By means of the described arrangement the operator is enabled to retain always 95 a uniform tension of the chain. This the operator effects by proper selection of the transmission of the toothed-wheels. This uniform tension of the chain is independent 100 of the distance apart of the shafts of the two sprocket-wheels E and F.

In the modified form illustrated in Figs. 4 to 7 the compulsory movement of the sprocket-wheel S¹ is also effected from the 105 sprocket-wheel E¹ but by means of a crank mechanism. The sprocket-wheel E¹ is formed so as to act as a crank disk which by means of the crank rod U¹ acts on the bearing of the sprocket-wheel S¹ that moves in 110 the straight guiding rails Y. The chain G¹ which passes over the sprocket-wheels E¹

and F^2 also passes over the guiding sprocket-wheel F^1 and the sprocket-wheel S^1 . Corresponding to the position of the sprocket-wheel E^1 relative to the sprocket-wheel F^2 5 the sprocket-wheel S^1 moves in the straight guide Y by means of the crank mechanism.

For the purpose of equalizing the uneven motion which is inherent to every crank mechanism the crank rod U^1 may be spring 10 operated, as shown in Fig. 7. In this instance the crank rod is made in two parts of which the part U^2 is hollow while the second part U^3 moves therein. Between these two parts a spring Z is inserted whereby the 15 crank rod may be shortened or lengthened during its motion.

I claim as my invention:

1. A driving chain gear for retarding the transport in sheet feeders comprising a 20 driving sprocket-wheel, a set of sprockets, a chain passing over all the sprockets, and a longitudinal member subject to a compulsory displacement, one of said sprockets being mounted on said longitudinal member.
2. A driving chain gear for retarding the transport in sheet feeders comprising a 25 driving sprocket-wheel, a set of sprockets, a chain passing over all the sprockets, and a longitudinal member subject to a compulsory displacement and performing a swinging motion, one of said sprockets being mounted on said longitudinal member.

Copies of this patent may be obtained for five cents each, by addressing the "Commissioner of Patents, Washington, D. C."

3. A driving chain gear for retarding the transport in sheet feeders comprising a 35 driving sprocket-wheel, a set of sprockets, a chain passing over all the sprockets, and a longitudinal swinging member, subject to a compulsory displacement, one of said sprockets being mounted on said longitudinal member.

4. A driving chain gear for retarding the transport in sheet feeders comprising a 40 driving sprocket wheel, a set of sprockets, a chain running over the sprockets, a longitudinal swinging member receiving its motion from the driving sprocket and adapted to displace one of said sprockets to effect a uniform tension of the chain.

5. A driving chain gear for retarding the transport in sheet feeders comprising a 45 driving sprocket-wheel, a set of sprockets, a chain passing over the sprockets, a longitudinal swinging member receiving its motion from the driving sprocket, one of said sprockets being mounted upon the longitudinal member, and a toothed wheel, and a toothed rack, both subject to compulsory displacement whereby the chain is tensioned.

Signed at Leipzig Germany, this 4th day of May 1915.

GEORG SPIESS.
